DISPLAY BOX

Robert P. Vuillemenot, Oradel, N. J., assignor to Maiden Form Brassiere Co., Inc., New York, N. Y., a corporation of New York

Application October 3, 1958, Serial No. 52,866

Term of patent 14 years

(Cl. D58—12)

Fig. 1 is a perspective view of a display box showing my new design;

Fig. 2 is a side elevational view thereof taken on a reduced scale;

Fig. 3 is a perspective view of the box in open position; and

Fig. 4 is a perspective view of the box taken in reverse position to that shown in Fig. 3.

This application is a continuation-in-part of my co-pending application, Serial No. D. 47,439, filed August 19, 1957.

I claim:
The ornamental design for a display box, as shown.
